(57) **CLAIM**

The ornamental design for a linear floor drain with side returns as shown and described.

DESCRIPTION

FIG. 1 is a front isometric view of a linear floor drain with side returns in accordance with the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the linear floor drain with side returns that form no part of the claim.
